UNITED STATES PATENT OFFICE.

PRESTON M. BRUNER, OF ST. LOUIS, MISSOURI.

CABLE RAILWAY.

SPECIFICATION forming part of Letters Patent No. 374,775, dated December 12, 1887.

Application filed March 10, 1887. Serial No. 230,440. (No model.)

To all whom it may concern:

Be it known that I, PRESTON M. BRUNER, of the city of St. Louis, in the State of Missouri, have invented a certain new and useful Improvement in Cable Railways, of which the following is a full, clear, and exact description, reference being had to the accompanying drawings, forming part of this specification, and in which—

10 Figure I is a vertical section through my improved railway, taken on line I I, Fig. III. Fig. II is a detail top view, part in horizontal section. Fig. III is a detail view looking at the inside of the upper part of the conduit, and is, so to speak, a section taken on line III III, Fig. I. Fig. IV is a detail vertical section, taken on line IV IV, Fig. III. Fig. V is a similar view illustrating a slight modification. Fig. VI is another similar view illustrating another slight modification.

15 My invention relates to certain improvements in cable railways; and it consists in features of novelty hereinafter more fully described, and pointed out in the claims.

20 Referring to the drawings, 1 represents the tracks fitting in chairs 2, having horizontal perforated projections or bases 3, through which pass bolts or rods 4 with nuts 5 on their outer ends.

25 6 represents the conduit or tube, made, preferably, of concrete, 7, and yokes or plates, 8, as in my patent, No. 345,616, issued July 13, 1886, the yokes or plates having in this case lugs 9 to receive rods 10, that surround the yokes and 30 are provided with nuts 11, by which they may be tightened. The function of these rods 10 is the same as that of the bands or straps L of my patent referred to. The inner ends of the rods or bolts 4 are connected to the yoke of 35 the tube or conduit, and tend, by tying the tube to the chairs of the track, to prevent the closing of the slot, and by turning the nuts 5 the slot can be to a certain extent enlarged.

40 12 represents arms corresponding to the arms O of my patent mentioned. Their function is described in the patent.

45 Inside of the upper part, 13, of the tube or conduit are plates 14, connected to the conduit at their lower edges and having heads 15 on 50 the upper edges. The heads 15 preferably fit under the inturned edges 16 of the conduit, (though they may fit outside, as shown in Fig.

V,) and they regulate the width of the slot through which the grip passes and through which vehicle-wheels are prevented from passing. These heads 15 prevent, to a great extent, the entrance of dirt and mud into the spaces between the plates and sides of the tube by closing or bridging across and covering the spaces between the plates and the sides 60 of the tube. The heads 15 are of sufficient width to permit of the adjustment of the plates without the spaces between the plates and the sides of the tube being exposed. The plates 14 are preferably made of spring metal, and 65 are connected by bolts 17 near their upper edges to the part 13 of the conduit. Now, in case of frost causing the expansion of the road-bed, the part 13 of the conduit will be compressed; but the plates 14, which regulate the 70 size of the grip-opening of the slot, will remain unmoved, or should they move, owing to frictional contact with the part 13 or to their being connected thereto, they can be easily and quickly set apart by the bolts 17, the 75 nuts of which can be reached through the slot. The slot will thus be, regardless of temperature, always the proper size, or should it vary it can easily be regulated.

80 As stated, the heads of the plates 14 may fit outside of the conduit proper, if preferred, (see Fig. V,) and instead of the plates being connected to the conduit, as shown in Figs. I and IV, where they have bases 21, through which pass bolts 22, they may be connected, 85 as shown in Fig. VI, by bolts 18 and washers 19. When connected as shown in Figs. I and IV, they would have openings or perforations 20 (see Fig. III) a suitable distance apart to permit the passage of dirt and mud that may 90 get between them and the upper part, 13, of the conduit. With the form of connection shown in Fig. VI, the dirt and mud would pass down through between the various washers 19, which would be some distance apart.

95 23 represents rods connecting the part 13 of the conduit to the sleepers of the tracks. They have nuts 24 at both ends, and by turning on these nuts the part 13 of the conduit may be expanded, if desired. The plates 14 are perforated at 25 (see Fig. IV) to allow access to the inner nuts, 24.

100 The road-bed consists of blocks 27, extending from either side of the conduit to the rail

on that side. They may be made narrow, as shown on the left-hand side of Fig. II, or wide, as shown on the right-hand side. Between the outer ends of these blocks and the ties of the tracks are placed strips 28, which are triangular in cross-section, and preferably have concave inner faces that receive convex faces formed on the outer ends of the blocks 27. The object of this construction is that when the frost in the street between either rail and the sidewalk expands the blocks 27, instead of being forced in a horizontal plane directly against the conduit, will rise or lift at their outer ends, owing to the shape of the strips, and thus the strain that will be brought upon the conduit by the expansion of the street between either rail and the sidewalk is prevented.

I claim as my invention—

1. In combination with the conduit or tube of a railway, the plates 14, when mud or dirt passages are left or provided at the bottom of

said plates, substantially as and for the purpose set forth.

2. In combination with the conduit or tube of a railway, the plates 14, having openings to permit the passage of mud and dirt formed by removing portions of the plates at their lower edges, as set forth.

3. In a railway, the conduit consisting of the combination of the concrete, plates embedded in the concrete and having perforated lugs, rods embracing the plates and passing through the lugs, and nuts on the rods, substantially as and for the purpose set forth.

4. In a railway, in combination with the conduit and the track, the blocks 27 and strips 28, formed substantially as and for the purpose set forth.

PRESTON M. BRUNER.

In presence of—

JAS. E. KNIGHT,
EDW. S. KNIGHT.
